Primary Examiner — David Muller(74) *Attorney, Agent, or Firm* — Fitch, Even, Tabin & Flannery LLP(57) **CLAIM**

I claim the ornamental design for a suction handle, as shown and described.

DESCRIPTION

FIG. 1 is a perspective view of an ornamental design for a suction handle;

FIG. 2 is a second perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a rear elevation view thereof; and,

FIG. 8 is a front elevation view thereof.

The broken lines shown in the drawings are included for the purpose of illustrating use and environment and form no part of the claimed design.

1 Claim, 3 Drawing Sheets(56)
